UNITED STATES PATENT OFFICE.

JAMES PINE, OF TROY, NEW YORK.

MOWING-MACHINE.

SPECIFICATION forming part of Letters Patent No. 349,740, dated September 28, 1886.

Application filed November 5, 1884. Serial No. 147,936. (No model.)

To all whom it may concern:

Be it known that I, JAMES PINE, of the city of Troy, county of Rensselaer, State of New York, have invented a new and useful Improvement in Mowing-Machines, of which the following is a specification.

My invention relates to certain improvements in mowing-machines, and which improvements have for their object to better adapt such mechanism to the uses for which they are designed.

Accompanying this specification, to form a part of it, there are three sheets of drawings, containing seven figures illustrating my invention, with the same designation of its parts by letter-reference used in all of them.

In the illustrations, Figure 1 is a perspective of a mowing-machine containing my invention and improvements. Fig. 2 is a representation in perspective, and as detached from the other mechanism, of the machine-shoe, the hinged plate to which the finger-bar attaches, the sickle and its connection with the pitman, the keeper-plate, and the latch which secures the keeper-plate in position; and this view also illustrates the end of the bar which connects with the shoe, and which bar forms a part of a tilting frame; and it shows, also, a part of a brace connecting the shoe side plate with the tilting frame, the parts thus illustrated being shown in larger proportion than at Fig. 1. Fig. 3 represents a section taken on the line $x'x'$ of Fig. 1. Fig. 4 is a horizontal section, in part, of the mowing-machine frame and an inclosure formed in the side thereof, illustrating, also, a coupler or clutch for connecting the axle of the machine with the geared mechanism which operates the pitman and sickle. This figure illustrates, also, the pivoted connection between the frame proper of the machine and the angle-rod forming a part of a tilting frame, and also the crank-connection with the pitman. Fig. 5 is a cross-section taken on the line $x''x''$ of Fig. 4; and Fig. 6 is a section through the line $x'''x'''$ of Fig. 1, and Fig. 7 a section through the finger-bar on the line $x''x''$ of Fig. 1.

The several parts of the machine are designated by letters of reference, and their function is described as follows:

The letter F' indicates the frame of the ma-

chine, which is preferably made in one piece of cast metal. This frame is constructed to have the sleeve f', for the passage of the axle A, (on which the frame rests,) and which sleeve is enlarged at f'', to inclose a coupler, which encircles the axle, and that is used to connect the axle in its rotation with the gear-wheels that communicate motion and power to the pitman and sickle. This frame is also constructed to have the side inclosure, f'', with said inclosure extending beyond the axle at the rear, and also extending forward in advance of the axle, the purpose of this inclosure being to contain the gear-wheels which connect the axle with the pitman and sickle, and to receive the bearings on which the gear-wheels located therein turn.

The letter b' designates a brace that attaches to the inner side of the front extension, f'', of said frame F', at right angles thereto, and also by its angular part, when extended rearward, connects with the sleeve f', where inclosing the axle, between the expansion of said sleeve at f'', and the outer end of this part of the sleeve where adjacent to the wheel.

My improvement upon older mowing-machine frames consists in locating the main frame so as to inclose the axle and mechanism connected with the latter to operate the sickle-bar, and have the mechanism that is inclosed within the main frame operating the pitman and sickle-bar on that side of the machine which is opposite to that where the sickle-bar is placed, as distinguished from the mechanism shown in the patent to W. A. Kirby, No. 142,111, of August 26, 1873, where the main frame is hinged by brackets to the axle, and in the Letters Patent to W. Gause, No. 257,858, dated May 16, 1882, where the mechanism operating the sickle is arranged on that end of the main axle which is adjacent to the sickle. At the front this inclosure f'' of the main frame F', by means of a jog made therein, is extended outwardly and horizontally in front of the adjacent tracking wheel at f'', to make room for the revolution of the disk-wheel on which the wrist-pin of the pitman P' is placed. At the front this extension of the inclosure f'' is made with an end opening, that is closed by means of a hinged cap, C', and the vertical slot i' is made in its side for the reciprocating traverse of the pitman.

The letter C² designates a hinged cover arranged in the top of said inclosure f³, whereby access can be had to the gear-wheels contained therein.

5 The letter K' designates a hinged cover that opens and closes a passage-way for the sleeve f', made in the frame, and by which access is had to the coupler mechanism.

The letter A' indicates the axle, which at 10 each of its ends, where projected through the hubs of the wheels W' W', is made with the ratchet-wheel R', and each of the hubs h' are made to have a pivoted pawl, p', adapted to engage with one of said ratchet-wheels, so that 15 as the wheels are moved to progress the machine these pawls will engage with the ratchets and cause the axle to turn with the wheels, and as the latter are moved rearward the pawls and ratchets will allow the wheels to turn on 20 the axle.

The letter C³ designates a clutch arranged to encircle the axle A' within the sleeve f' of the frame F'.

The letter v' designates an annular groove or 25 recess in the coupler, and I' a crescent-formed and vertically-arranged shipper adapted to enter said groove or recess, and the letters t' indicate teeth arranged on the end of the coupler.

30 The letter L' designates a lever that is pivoted to a standard, d', with the latter attached to and projected from the cover K', and the letter b' indicates a bar connecting said lever with the shipper I', so that as said lever is moved 35 back and forth on a line with the axle the clutch C³ is moved back and forth also, with its teeth adapted to engage with other teeth to communicate motion and power thereto, as will be subsequently described herein.

40 The letter a' indicates a pin on the back of the lever L', and the letters o' openings in the standard d', to receive said pin, and thus secure the lever in an adjusted position. The pivot-pin of this lever is designated by p². It 45 is made with the head u' and adapted to pass through the lever, and to have the spring s' arranged upon it between the head u' and the outer face of the lever, the function of this spring being to keep the clutch-lever up against 50 the standard and the pin a' in one of the holes o' when the lever is adjusted.

The letter l' indicates a slot made in the cover K', for the passage of the clutch-lever bar b' as it is moved to connect or disconnect the 55 clutch.

The letter g' designates a groove formed in the axle, parallel to its sides, and n' a pin attached to the inner surface of the clutch-sleeve, so as to be within said groove and to prevent 60 the clutch from turning on the axle. While I have shown a groove thus made in the axle and a pin arranged on the inner face of the clutch-sleeve, if desired, a feather may be formed on the axle and a groove arranged on 65 the inner face of the clutch-sleeve adapted to receive such feather, and which construction will have the same function.

The letter G' indicates a gear-wheel having a sleeve, S', arranged on the machine-axle A', and to which sleeve the gear-wheel G' is attached, so as to move with it. The said sleeve and gear-wheel are free to move on the machine-axle, excepting when the coupler-teeth t' on the end of the said sleeve S' are in engagement with the teeth t' of the clutch-sleeve, 70 and then said gear-wheel and sleeve S' move with the machine-axle. As this gear-wheel G' and its connected sleeve are placed, when the clutch C³ is moved out on the axle its teeth engage with those on the sleeve S', and thus power 75 and motion are communicated to the latter and the wheel G'.

The letter P² indicates a pinion arranged to engage with and gear into the said wheel G', before described, and G² indicates another 80 gear-wheel, which, with the said pinion P², is formed on and so as to move with the sleeve S', arranged on the rod r' for a journal, the said journal being secured in the side walls of the inclosure f³ through openings therein by means of 85 a head, h², on one end of the journal, and a slot, i', in the other end, the slot being adapted to receive a key where the end of the journal projects beyond the side wall of the inclosure. As thus made, said sleeve S², journal r', pinion 90 P², and the connected gear-wheel G² can be removed and replaced by a duplicate of the parts should wear or accident render such a change necessary, and this can be done by simply driving out the key, and then the journal, the said sleeve, wheel, and pinion can be taken from the inclosure, and, if desired, a 95 duplicate of the parts put in the same position.

The letter G³ indicates a beveled gear-wheel, and p⁴ a pinion, and S³ a sleeve on which said beveled gear-wheel and pinion are secured, so 100 as to turn with said sleeve.

The letter m' indicates a journal for the sleeve S³ and its connected bevel-wheel and pinion to turn in. This journal is arranged in 110 opposite openings in the sides of the inclosure f³, and said journal m' is held in place by a head, h³, on one of its ends and a slot, i³, made in its other end, adapted to receive a key where said slotted end of the journal projects beyond the 115 wall of the inclosure f³, and so that the said sleeve S³, its connected beveled gear-wheel G³ and pinion p⁴, and journal m' can be removed and its parts replaced by the same procedure as the sleeve S², gear-wheel G², and pinion P². 120

The letter D' indicates a beveled pinion arranged within the forward extension of the inclosure f³, the shaft of said wheel D' having its bearing in the machine-frame at n². This beveled pinion D' is adapted to engage with 125 the beveled gear-wheel G³, and there is arranged on the outer face of this beveled pinion a crank-wheel, M', constructed with a wrist-pin, O², to which is pivoted one end of the pitman P', and by which connection there is 130 communicated reciprocating motion to the pitman when the said pinion actuates the wheel M'.

The letter B' designates a bar that has at

one end a connected ring, C^4 , that loosely fits into an annular groove, g^2 , made in the forward extension of the inclosure f^3 back of the cap C , and by which ring and groove the said 5 bar is hinged thereat, so as to be on its lower end moved up and down on such connection. The lower end of this bar B' is attached to the vertical plate E' at d^2 , near its rear end, and by an angularly-placed brace, b^2 , the front end 10 of the plate E' is connected with the said bar B' .

The letter R^2 designates a rod, which at its rear end is pivoted to the machine-frame at m^2 , and at its front end said rod is attached to the bar B' , as indicated at d^2 , the latter and 15 the said rod forming the tilting frame D^2 of the machine, and by means of which the shoe and the operating mechanism connected therewith may be raised from off the ground when the cutting mechanism is not in operation.

20 The letter L^2 designates a lever, which is attached to the side of the segment N' , the latter being pivoted to the brace b^2 . This segment is formed with the groove u^2 in its rim to receive a chain or rope, I^2 , one end of which 25 is secured to the segment and the other end attached to the rod R^2 , as shown at d^2 . By means of the lever the tilting frame is raised.

The letter l^2 designates a latch on the standard d^2 , which holds the lever down when the 30 tilting frame is raised.

The letter E' indicates a plate that is attached to the end of the bar B' , and which as attached is slightly inclined from a perpendicular at its top toward the pole of the machine. 35 The middle of this plate, from its top edge down to a line coincident with the top of the shoe S^4 , is cut out, as indicated at o^2 , for the passage of the pitman P' .

The letter w' designates a plate that is arranged parallel to the plate E' , and attached to the latter by a pivot-bolt, d^2 , having its head on the inner face of the said plate E' . At the outer face of the plate w' there are projected at right angles thereto the ears $e^2 e'$, and 45 the latter are made to have hinge-eyes for the passage of a hinging-bolt, and they are arranged to be coincident with the hinging-eyes in the ears $e^2 e'$, that are projected upward from the top surface of the shoe S^4 , so that a hinging-bolt can be passed through both sets of eyes and the hinging-connection indicated at 50 H' produced.

The letter h^4 designates an adjustable hinged connection made between the shoe S^4 and the side of the plate E' , at its front end. This hinged connection is produced by a lug, y^4 , that is projected upward from the face of the shoe, and which is constructed with an eye, o^4 , for a hinging-pin, and the letter y^2 designates an angle-plate, one face of which is provided with a vertical slot, i^2 , and a set-screw, m^2 , to connect it adjustably to the vertical face of the plate E' , and the other angle-face of the plate y^2 is made with a hinge-eye, that, 60 when in position, is coincident with the eye in the lug y^4 , and so that when a hinging-pin is passed through both of the eyes the hinged

connection h^4 is made. As thus constructed and arranged, the shoe S^4 and its attached cutting mechanism can be raised or depressed at 70 the front by means of the pivot-bolt which connects the plates E' and w' and the slot i^2 and set-screw m^2 .

The letter U' designates the finger-bar, made with the usual fingers, and the letters u^2 indicate guides arranged on the upper surface and inner edge thereof; u^4 , the fingers of the bar, which fingers are slotted horizontally, as indicated at b^4 .

The letter g^2 designates a groove made in 80 the top of the finger, and the letter T' indicates the serrated sickle, adapted to be moved in the groove g^2 and the slots b^4 of the fingers. The upper surface of the sickle, near its outer end, is provided with the pin r^4 , slightly projected from its surface and enough so as to pass the slots of the fingers and guide-plates, and at the same time be adapted to engage with and draw from out the front end of the finger any grass that would choke the operations of the cutter mechanism.

The letters n^2 indicate projecting points on the bottom of the sickle, adapted to draw out from the groove g^2 any grass that might be drawn in there to interfere with the operation of the cutter mechanism.

The letter d^6 indicates a lug formed on the front edge of the sickle T' , near its inner end, and E^2 an opening or eye formed in the front face of the said lug to receive the angular end 100 of the pitman. The end of the pitman P' , where it connects with the sickle, is bent at right angles to its other part, as indicated at a^2 in the annex to Fig. 2 designated at Z .

The letter K^2 indicates a keeper, and l^2 a 105 latch, both of which have a pivoted connection made by the same pivot, m^2 , arranged in the overhanging plate z^2 of the finger-bar, the latch being arranged to be above the keeper. This keeper K^2 is adapted to be swung around 110 on its pivot adjacently to the pitman where the latter is angularly bent to connect with the sickle-eye, but so as not to be in contact with it thereat, the turned-down end a^2 of the keeper being secured at a point on the shoe-surface where it will allow the free movement 115 of the sickle and pitman, but where it will prevent the latter from working out of the sickle-eye.

The letter J' indicates a catch-pin that is upwardly projected from the top of the shoe and formed with the horizontal slot i^2 in its side, which slot the keeper K^2 enters when it is swung on its pivot around toward the pitman-connection, and which engagement with the 120 slot will prevent it from swinging in too near the pitman.

The letter V' designates a pin on the under side of the latch l^2 , and o^4 an opening made through the keeper K^2 and into the shoe for the said pin to enter when the latch is moved over the face of the keeper and the pin comes over said opening, the purpose of which latch and pin is to secure the keeper from moving 125

out from its location with reference to the pitman, while the catch-pin J' and its slot i' prevent the keeper from swinging in too far near the pitman.

- 5 The letter P^3 indicates the tongue, which is hinged to the sleeve f' by means of ears $e^3 e^4$, upcast therefrom, and a hinging-bolt, b^5 , which passes through the ears and the intermediate-ly-placed pole.
- 10 The letter A^2 designates a standard that is upwardly projected from the brace b^3 , and this standard is constructed with a series of holes, o^5 , arranged in line and made transversely therein. These holes are adapted to receive a headed bolt, n^4 , that is passed through the pole P^3 in a location therein that is opposite to the row of holes in the standard, the said bolt being made with a nut to secure the parts as thus placed.
- 15 The letter Y' designates a clevis-bar, which throughout its length is arranged with a row of transversely-made holes, a^4 , and this clevis-bar at its upper end is hinged to the under side of the pole P^3 at h^5 .
- 20 The letter M^2 indicates a pivot-plate made with ears $e^4 e^4$, horizontally projected from the front thereof, each of said ears being made with an opening for the passage of a linchpin or bolt. These ears e^4 are made to form a 25 pivot-connection with the double-tree d^3 , which is secured therein by means of the bolt b^7 , that is passed through the ears e^4 and the intermediate-ly-placed double-tree.
- 25 The letters $e^5 e^6$ designate another set of ears that are vertically projected from the back edge of the plate M^2 , said ears being made with eyes for the passage of a headed bolt, b^8 , and so arranged that when the clevis-bar is placed between the said ears e^5 , and the bolt b^8 30 is inserted through the ears and intermediate-ly-placed clevis-bar, a pivoted connection is made with the latter thereat.
- 30 The letter r^5 designates a chain or rope connecting the lower end of the clevis-bar with the bar B' of the tilting frame of the machine to which the cutting mechanism attaches.
- 35 By the foregoing described connection of clevis, double-tree, and tilting frame the draft-line exerted to draw the machine may be vertically raised or lowered by the relative height at which the clevis-bar connects with the machine. The connection by the rope or chain r^5 being made with the tilting frame D^2 , to which the cutting mechanism attaches, a portion 40 of the draft force is exerted to hold up the latter, and to thus better adapt it for passing over undulations and irregularities in the ground. Another advantage resulting from this construction of clevis-bar, tilting frame, and double-tree is, that the whiffletrees are prevented from tilting or dropping, and the draft-animals from getting their feet over the traces.
- 45 The tilting frame D^2 is arranged to have its hinging attachment so made that the center of the pivot on which the rod R^2 is hinged at m^2 shall be in a line with the center of the wrist-

pin wheel M' , to which the crank end of the pitman attaches, and with the hinging-ring C' of the bar B' so arranged in the groove g^2 of the frame-offset that the center of said ring C' shall be on a line with that of the center of the wheel M' . As thus conditioned, when the tilting frame and the cutter apparatus are elevated or depressed the sickle will have the same throw in its guides, and as the tilting frame is hinged it allows the cutting apparatus to be elevated without throwing or crowding the finger-bar ahead or drawing it back from a right angle with the main frame. All the sleeves upon which are placed spur-wheels, gear-wheels, and pinions as arranged to receive and transmit power from their position within the inclosure f^3 , made in the frame F' , are constructed to run loosely and free on their bearings.

50 While I prefer to make the frame F' in one piece of cast metal, yet it may be made in several parts and connected together, provided the same arrangement and relative construction of its inclosures to receive the axle, the sleeve, the gear-wheels and pinions, and the disk-wheel of the pitman are retained.

55 The cutter mechanism being attached to the shoe S^4 , and the latter hinged at H' to the plate w' , with the latter plate pivoted to the plate E by the bolt d^5 , the front end of the shoe being adjustably hinged to the plate E by the connection h^4 , before described, with the latter hinge and the hinge H' in line with the sickle-eye, I am enabled to operate the cutting mechanism with a little upthrow at the front, if desired, and the rear edge of it low down close to the ground, and should the outer end of the finger-bar strike an obstruction it cannot necessarily change the traverse of the sickle, as it would were the connection between the latter and the pitman made above the hinged line of the shoe.

60 Having thus described my invention, what I claim, and desire to secure by Letters Patent, is—

1. The combination, with the carriage-axle A' , of the frame F' , having the axle projected through it, substantially as shown and described, and comprised of the tubular sleeve f' , formed with the enlarged portion f^2 , the transversely-arranged receptacle f^3 , having the brace b^3 connected to the tubular sleeve, and provided with the cover C^2 , and the forward extension, f^4 , provided with exterior annular groove, g^2 , and cap C' , all substantially as described, and for the purpose stated.

2. In a mowing-machine main frame, the combination of the sleeve f' , having the enlargement f^2 , made with a top opening therein, and the cover K' , the inclosure f^3 , connecting with and arranged at right angles to said sleeve, said inclosure having a top opening with the cover C^2 , hinged to the open-end front offset extension, f^4 , of said inclosure, having the hinged cap C' , and the slot i^6 , made in the side of said extension, the said parts being ar-

ranged with reference to each other and constructed substantially as and for the purposes set forth.

3. In a mowing-machine, the combination of the sleeve f' , made as described, the slotted cover K' , hinged to close an opening in the top of said sleeve, the lever L' and standard d' , attached to the top of said cover, the clutch C' , constructed to encircle the machine-
10 axle within the enlargement of said sleeve, said clutch being made with the teeth t' and the encircling-groove v' , the shipper I' , and the bar b' , made to connect said shipper and lever, substantially as and for the purposes
15 set forth.

4. In a mowing-machine, the combination of the sleeve f' and the clutch C' , made and arranged with reference to each other and the machine-axle substantially as described, the
20 sleeve S' , arranged on the said axle, the gear-wheel G' , arranged on said sleeve S' , the sleeve S' , arranged on the bearing-rod r' , the gear-wheel G^2 and pinion P^2 , arranged on said sleeve S^2 , the sleeve S^3 , arranged on the bearing-rod m' , the beveled gear-wheel G^3 and spur-
25 wheel p^4 , arranged on said sleeve S^3 , and the beveled pinion D' and disk M' , the latter having the wrist-pin O^2 on the outer face, and said parts being arranged to operate substantially
30 in the manner as and for the purposes set forth.

5. In a mowing-machine, the combination of the inclosure f^3 , constructed and arranged with reference to the machine-axle and the operation of the sickle as shown, the sleeve
35 S' , made with the gear-wheel G' and arranged on the machine-axle, the sleeve S^2 , having arranged thereon the gear-wheel G^2 and pinion P^2 , and provided with the removable pintle-shaft or bearing-rod r' , the sleeve S^3 , having
40 arranged thereon the spur-wheel p^4 and beveled gear-wheel G^3 , and provided with the removable pintle-shaft or bearing-rod m' , the disk-wheel M' , made with the beveled pinion D' and wrist-pin O^2 , and the pitman P' , sub-
45 stantially as and for the purposes set forth.

6. In a tilting frame for a mowing-machine, the combination of the coupling-bar B' , made with the ring C' , adapted to hinge into a groove on the forward extension of the main
50 frame, and the angle-rod R^2 , pivoted to the rear of the main frame at n^2 , with its pivotal center thereat coincident with the center of

the ring C' and the center crank-shaft, with the front end of said rod R^2 connected with the bar B' at d^2 , as and for the purposes set forth. 55

7. In a mowing-machine, the combination of the shoe S^4 , the hinge H' , the plate w' , pivoted to the plate E' , and the vertically-adjustable hinge h^4 , constructed to connect said shoe to the plate E' , substantially as and for the 60 purposes set forth.

8. In a mowing-machine, the combination of the pitman-rod made with the angular end a^2 , the sickle T' , made with the lug d^6 , having the eye E^2 , the keeper K^2 , the latch l^2 , and catch-pin J' , said parts being constructed and arranged to operate substantially as and for the purposes set forth. 65

9. In a mowing-machine, the combination of the pitman P' , made with the angular connecting end a^2 , the sickle made with the lug d^6 , having the eye E^2 on its upper side, the pivoted keeper K^2 , made with the turned-down end a^2 , the catch J' , and the pivoted latch l^2 , said parts being constructed and arranged to operate substantially in the manner 70 as and for the purposes set forth.

10. The combination, with the tongue of the machine, the tilting frame, and the double-tree, of the clevis-bar Y' , having a series of 80 holes, a^4 , and pivotally connected to the tongue of the machine, with its lower end depending and flexibly connected to the bar B' of the tilting frame, and the clevis M^2 , having perforated ears e^5 , adjustably bolted to the clevis-bar, and the ears e^4 , pivotally connected to the double-tree, substantially as described, 85 and for the purpose stated.

11. In a mowing-machine, the combination of the frame F' , made with the sleeve f' , encircling the machine-axle, the pole P^3 , hinged to said sleeve where encircling the axle, the standard A^2 , made with the holes o^5 , and upwardly projected from the brace b^8 , and the bolt n^4 , said parts being constructed and arranged to operate substantially in the manner 90 as and for the purposes set forth.

Signed at Troy, New York, this 28th day of July, 1884, and in the presence of the two witnesses whose names are hereto written.

JAMES PINE.
